(57) **CLAIM**

(21) Appl. No.: **29/846,086**

The ornamental design for a combined electrical wall outlet cover with extended cord outlet, as shown and described.

(22) Filed: **Jul. 13, 2022**

DESCRIPTION

(51) LOC (15) Cl. 13-03

FIG. 1 is a front view of a combined electrical wall outlet cover with extended cord outlet showing the new design. FIG. 2 is a front view thereof, shown in an environment. FIG. 3 is a left side view thereof.

(52) U.S. Cl. **D13/137.4**

FIG. 4 is a left side view thereof, shown in an environment. FIG. 5 is a right side view thereof, shown in an environment. FIG. 6 is a top view thereof.

(53) USPC **D13/137.4**

FIG. 7 is a bottom view thereof, shown on an environment. FIG. 8 is a back view thereof, shown in an environment. FIG. 9 is an enlarged partial view taken from FIG. 8.

(58) **Field of Classification Search**

FIG. 10 is an enlarged partial view taken from FIG. 8. FIG. 11 is a back perspective view thereof, shown in an environment.
